UNITED STATES PATENT OFFICE.

ALFRED SWENSEN, OF CICERO, ILLINOIS, ASSIGNOR TO THE CABLE COMPANY, OF CHICAGO, ILLINOIS, A CORPORATION OF ILLINOIS.

AUTOMATIC MUSICAL INSTRUMENT.

1,321,860.

Specification of Letters Patent. Patented Nov. 18, 1919.

Application filed October 9, 1916. Serial No. 124,690.

To all whom it may concern:

Be it known that I, ALFRED SWENSEN, a citizen of the United States, residing at Cicero, in the county of Cook and State of Illinois, have invented new and useful Improvements in Automatic Musical Instruments, of which the following is a full, clear, concise, and exact description, reference being had to the accompanying drawings, forming a part of this specification.

My invention relates to automatic musical instruments, and, more specifically, to a device for varying the degree of air-tension produced by an air-pump.

Among the objects of my invention is that of providing a device of this character which shall be simple in construction, efficient in operation, and easy of adjustment.

In the drawings, in which one embodiment 20 of my invention is shown—

Figure 1 is a front elevation of a player-piano, the upper front panel being broken away to show the roll-box, and the lower front panel being broken away to show the 25 air-pump and expression-device;

Fig. 2 is a section through the expression-device, on the line 2—2 of Fig. 3;

Fig. 3 is a section through the expression-device, on the line 3—3 of Fig. 2;

Fig. 4 is a detail sectional view of part 30 of a pneumatic-finger; and

Fig. 5 is a bottom view of the part shown in Fig. 4.

Referring now to the drawings in detail, 35 the player-piano shown comprises a casing 10, a roll-box 11 located in the upper part of the casing, a motor-driven air-pump 12 for exhausting the air from the action wind-chest and music roll motor, conduits 13 and 14 leading from the wind-chest to the air-pump, an expression-device 15 for varying the degree of air-tension produced in the wind-chest by the air-pump, and a conduit 16 leading from the expression-device to the 40 conduit 13.

The air-pump operates to exhaust the air from the wind-chest through the conduits 13 and 14, and the expression-device operates to modify the air-tension produced 45 by the air-pump by admitting atmospheric air more or less freely through the conduit 16 to the conduit 13. The expression-device 50 15 may be controlled automatically, from the note-sheet 16, or manually, by means 55 of the valve-mechanism 17.

The expression-device itself comprises a series of chambers 18, 19, 20, 21, and 22, separated by partitions 23, 24, 25, and 26, each two adjacent chambers being in communication with each other through one of the ports 60 27, 28, 29, and 30. The chamber 18 is in communication with the atmosphere through the port 31, and the chamber 22 is in communication with the conduit 16 through the port 32. The flow, through the ports 27, 28, 29, and 30, is controlled by means of substantially similar valve-mechanisms 33, 34, 35, and 36, respectively. Each of these valve-mechanisms is movable, from a position in which it permits a substantially free 70 flow of air through its port to a position in which it offers a yielding resistance to the flow of air, by means of a pneumatic 37 which acts on a lever 38, on which the valve proper 39 is yieldably mounted. An adjustable stop 40 limits the valve-closing movement of the lever 38. A spring 40^a acts on the lever 38 and tends to hold the pneumatic 37 collapsed. Each of the pneumatics 37 is controlled from the tracker 41 80 through one of the conduits 42, 43, 44, and 45, leading from the tracker to the junction and valve-block 46, one of the conduits 47, 48, 49, and 50, leading from the junction and valve-block 46, to the valve-actions 51, 52, 53, and 54, respectively, and one of the conduits 55, 56, 57, and 58, leading from the valve-actions to the pneumatics 37, respectively. The port 31 is controlled by means of an adjustable, yielding, pressure-operated 90 valve-mechanism 58^a.

The lever 38 is pivotally mounted at 59 on a fulcrum-block 60 and is provided, at one end with a felt pad 61 for engagement with the pneumatic 37, and, at its other end, with 95 a felt pad 62 for engagement with the stop 40. The valve 39 is secured to a stem 63, the upper end of which slides in a guide 64, and the lower end of which extends through an opening in the lever 38 and has a washer 65 100 slipped over it and a nut 66 threaded onto it. For yieldably supporting the valve 39 on the lever 38, a coil-spring 67 is provided which surrounds the stem 63. When the valve 39 is opened, this spring acts on the 105 valve to hold it as far from the lever 38 as the nut 66 will permit. When the valve is raised by the lever 38, the spring 67 is further compressed, the degree of compression being determined by the setting of the stop 110

40. To prevent fluttering of the valve 39 when in raised position, a bellows dash-pot 68 is interposed between the valve and the lever 38, being supported on the latter and 5 having a finger 69 on its movable leaf extending between the spring 67 and the valve 39. The bellows dash-pot consists, in this instance, of a small bellows provided with a small leak-vent not shown, the arrangement of which may be substantially the same 10 as shown in my Patent No. 1,231,809, dated July 3, 1917, upon automatic musical instruments, application filed June 28, 1916, which prevents a too rapid vibration of the bellows 15 and thus checks any undesirable fluttering of the valve 39, but permits the normal operation of the valve and compression of the spring 67. The finger 69 has a circular recess 69^a (Figs. 4 and 5) in the lower side, in 20 which the upper end of the spring 67 seats, and an opening 69^b, through which the stem 63 extends. For convenience, a slot 69^c leads to the opening 69^b, through which slot the stem 63 can be passed, in assembling. If de- 25 sired, the springs 67 for the different valves 39 may be made of different strengths. Each stop 40 comprises a bent lever 70, pivotally mounted on a fulcrum 71 and adjusted by means of a button 72. The button is se- 30 cured to a stem 73, which extends through a notch 74 on the lever and is threaded into a U-shaped nut 75, the arms of which straddle the lever 70 to prevent the nut from rotating when the button 72 is turned. Threads on 35 the stems 73 are made left-hand, so that clock-wise turning of each button 72 causes the horizontal arm of the respective lever to be raised to permit the corresponding pad 62 to rise higher and a greater tension to be 40 put on the respective spring 67 when its pneumatic 37 is expanded. The fulcrum 71 comprises a screw 76 extending through an opening 77 in the lever 70, and a felt washer 77^a between the lever 70 and the wall of the 45 chamber. The screw 76 extends loosely through the opening 77 to permit the lever to move freely, and a leaf-spring 78, secured to the wall of the chamber, is provided for supporting the lever 70 to hold the lower 50 edge of the opening 77 against the screw 76 and thus prevent rattling.

The valve-mechanism 58^a comprises the valve proper 79, a bent leaf, spring-lever 80 for supporting the valve 79, a button 81 for 55 adjusting the tension of the spring-lever 80, and a bellows dash-pot 82 for preventing fluttering of the valve 79. The construction of the bellows dash-pot 82 may be substantially the same as that of the bellows dash- 60 pot 68, already described. The button 81 is secured to a stem 83, which is threaded into a U-shaped nut 84, which straddles the spring-lever 80 to prevent the nut from rotating. The thread, on the part of the stem 65 83 engaging the nut, is made right-hand, so

that clock-wise turning of the button 81 will increase the resistance of the valve 79 to the flow of air. The valve-actions 51, 52, 53, and 54, may be of any usual or suitable type. Each comprises a double valve 85, actuated 70 by a diaphragm 86 controlled from the tracker. In the lowered position of each valve 85, the respective pneumatic 37 is in communication with the exhaust in the valve-action wind-chest 87 and, through the 75 conduit 88, with the exhaust in the chamber 22 (the pressure inside and outside of the pneumatic thus being substantially equal); and in the raised position of the valve 85 the pneumatic 37 is in communication with the 80 atmosphere, which causes the pneumatic to expand and move the lever 38 until the pad 62 strikes the stop 40, the lever 38 in its movement bringing the valve 39 into position to retard the flow of air through its 85 port. The manually operable valve-mechanism 17 comprises a slide-valve 89, movable to admit air selectively to any one of the conduits 47, 48, 49, and 50.

In operation, the air-pump 12 is driven 90 to exhaust air from the wind-chest through the conduits 13 and 14, and the expression-device 15 is operated to modify the air-tension, produced by the air-pump, by admitting air more or less freely through the conduit 16 to the conduit 13, such operation of the expression-device being controlled either automatically, by means of the perforations in the note-sheet 16^a, or manually, by means of the slide-valve 89. By means of the note- 95 sheet, any one, or any combination, of the valve-mechanisms 33, 34, 35, and 36, may be moved to a position to restrict the flow of air through their respective ports. If all of the valves are open, the flow of air 100 through the expression-device is practically unimpeded, except by the yielding valve 79. By adjusting the buttons 72, so that each of the yielding valves will offer a different degree of resistance to the flow of air, and by 105 using various combinations of the yielding valves, the total resistance offered to the flow of air through the expression-device may be varied, either gradually or suddenly, over a wide range. This variable resistance 110 of the flow of air through the expression-device, of course, results in a corresponding variation of the air-tension produced in the conduit 14 and wind-chest of the instrument, the tension in the wind chest increasing with 115 the increased resistance in the expression-device and decreasing as the resistance decreases.

Having thus described my invention what I claim as new and desire to secure by Letters Patent is:—

1. An automatic musical instrument comprising an exhaust air-pump and means for varying the degree of air-tension produced by said air-pump comprising a chamber in 130

- communication with said air-pump and having an air-admission port, and means for controlling said port including a movable member, a valve, and yieldable means acting between said member and said valve; said member being movable in one direction to move said valve from said port and in another direction to act upon said yieldable means to cause said valve to yieldingly obstruct the flow of air through said port. 6
2. An automatic musical instrument comprising an exhaust air-pump and means for varying the degree of air-tension produced by said air-pump comprising a chamber in communication with said air-pump and having an air-admission port, and means for controlling said port including a movable member, a valve, yieldable means acting between said member and said valve, and means for actuating said member; said member being movable in one direction to move said valve from said port and in another direction to act upon said yieldable means to cause said valve to yieldingly obstruct the flow of air through said port. 15
3. An automatic musical instrument comprising an exhaust air-pump and means for varying the degree of air-tension produced by said air-pump comprising a chamber in communication with said air-pump and having an air-admission port, and means for controlling said port including a movable member, a valve, yieldable means acting between said member and said valve, and sheet-controlled means for actuating said member; said member being movable in one direction to move said valve from said port and in another direction to act upon said yieldable means to cause said valve to yieldingly obstruct the flow of air through said port. 20
4. An automatic musical instrument comprising an exhaust air-pump and means for varying the degree of air-tension produced by said air-pump comprising a chamber in communication with said air-pump and having an air-admission port, and means for controlling said port including a movable member, a valve, yieldable means acting between said member and said valve; and a pneumatic for actuating said member; said member being movable in one direction to move said valve from said port and in another direction to act upon said yieldable means to cause said valve to yieldingly obstruct the flow of air through said port. 25
5. An automatic musical instrument comprising an exhaust air-pump and means for varying the degree of air-tension produced by said air-pump comprising a chamber in communication with said air-pump and having an air-admission port, and means for controlling said port including a lever, a valve, and yieldable means acting in one direction upon said lever and in another direction upon said valve; said lever being movable to move said valve from a position in which it does not materially obstruct the flow of air through said port to a position in which it is yieldably held by said yieldable means to obstruct said flow. 30
6. An automatic musical instrument comprising an exhaust air-pump and means for varying the degree of air-tension produced by said air-pump comprising a chamber in communication with said air-pump and having an air-admission port, and means for controlling said port including a movable member, a valve, yieldable means acting between said member and said valve, and a stop for limiting the action of said member upon said yieldable means; said member being movable in one direction to move said valve from said port and in another direction to act upon said yieldable means to cause said valve to yieldingly obstruct the flow of air through said port. 35
7. An automatic musical instrument comprising an exhaust air-pump and means for varying the degree of air-tension produced by said air-pump comprising a chamber in communication with said air-pump and having an air-admission port, and means for controlling said port including a movable member, a valve, yieldable means acting between said member and said valve, and an adjustable stop for limiting the action of said member upon said yieldable means; said member being movable in one direction to move said valve from said port and in another direction to act upon said yieldable means to cause said valve to yieldingly obstruct the flow of air through said port. 40
8. An automatic musical instrument comprising an exhaust air-pump and means for varying the degree of air-tension produced by said air-pump comprising a chamber in communication with said air-pump and having an air-admission port, and means for controlling said port including a movable member, a valve, yieldable means acting between said member and said valve, and a dash-pot member for said valve to prevent fluttering of the valve; said movable member being movable in one direction to move said valve from said port and in another direction to act upon said yieldable means to cause said valve to yieldingly obstruct the flow of air through said port. 45
9. An automatic musical instrument comprising an exhaust air-pump and means for varying the degree of air-tension produced by said air-pump comprising a chamber in communication with said air-pump and having an air-admission port, and means for controlling said port including a movable member, a valve, yieldable means acting between said member and said valve, and a bellows dash-pot member for said valve to prevent fluttering of the valve; said mov- 50

- able member being movable in one direction to move said valve from said port and in another direction to act upon said yieldable means to cause said valve to yieldingly obstruct the flow of air through said port.
10. An automatic musical instrument comprising an exhaust air-pump and means for varying the degree of air-tension produced by said air-pump comprising a chamber in communication with said air-pump and having an air-admission port, and means for controlling said port including a movable member, a valve, yieldable means acting between said member and said valve, a dash-
15 pot member for said valve to prevent fluttering of the valve, and means for actuating said movable member; said movable member being movable in one direction to move said valve from said port and in another direc-
20 tion to act upon said yieldable means to cause said valve to yieldingly obstruct the flow of air through said port.
11. An automatic musical instrument comprising an exhaust air-pump and means for varying the degree of air-tension produced by said air-pump comprising a chamber in communication with said air-pump and having an air-admission port, and means for controlling said port including a movable
25 member, a valve, yieldable means acting between said member and said valve, a dash-
30 pot member for said valve to prevent fluttering of the valve, and a pneumatic for actuating said movable member; said movable
35 member being movable in one direction to move said valve from said port and in another direction to act upon said yieldable means to cause said valve to yieldingly obstruct the flow of air through said port.
- 40 12. An expression-device for varying the degree of air-tension produced by an air-pump, comprising a chamber in communication with said air-pump and having an air-admission port, and means for controlling
45 said port including a movable member, a valve, and yieldable means acting between said member and said valve; said member being movable in one direction to move said valve from said port and in another direc-
50 tion to act upon said yieldable means to cause said valve to yieldingly obstruct the flow of air through said port.
13. An expression-device for varying the degree of air-tension produced by an air-
55 pump, comprising a chamber in communication with said air-pump and having an air-admission port, and means for controlling said port including a movable member, a valve, yieldable means acting between said
60 member and said valve, an adjustable stop for limiting the movement of said member, and means for actuating said member; said member being movable in one direction to move said valve from said port and in another direction to act upon said yieldable means to cause said valve to yieldingly obstruct the flow of air through said port.
14. An expression-device for varying the degree of air-tension produced by an air-pump, comprising two chambers, a port affording communication between said chambers, an air-inlet port to one of said chambers, the other chamber being provided with means affording communication with the air-pump, a yielding valve for said inlet port actuated by the air-pressure on said valve, and means for controlling the other said port including a movable member, a valve, and yieldable means acting between said member and said valve; said member being movable in one direction to move said valve from said port and in another direction to act upon said yieldable means to cause said valve to yieldingly obstruct the flow of air through said port.
15. An expression-device for varying the degree of air-tension produced by an air-pump, comprising two chambers, a port affording communication between said chambers, an air-inlet port to one of said chambers, the other chamber being provided with means affording communication with the air-pump, a yielding valve for said inlet port actuated by the air-pressure on said valve, and means for controlling the other said port including a movable member, a valve, yieldable means acting between said member and said valve, an adjustable stop for limiting the movement of said member, and means for actuating said member; said member being movable in one direction to move said valve from said port and in another direction to act upon said yieldable means to cause said valve to yieldingly obstruct the flow of air through said port.
16. A device for varying the degree of air-tension produced by an air-pump, having a series of ports through which the same air flows successively, yielding valve-means for controlling the flow through one of said ports, and means for controlling the flow through another of said ports comprising a movable member, a valve yieldably supported with respect to said member, and means for mounting said member to move said valve from a position in which it does not materially obstruct the flow of air through its port to a position in which it offers a yielding resistance to said flow; said port-controlling device being in series arrangement, whereby their effect is cumulative.
17. A device for varying the degree of air-tension produced by an air-pump, having a series of ports through which the same air flows successively, yielding valve-means for controlling the flow through one of said ports, and means for controlling the flow through another of said ports comprising a movable member, a valve yieldably supported with respect to said member, means

for mounting said member to move said valve from a position in which it does not materially obstruct the flow of air through its port to a position in which it offers a yielding resistance to said flow, and means for actuating said member; said port-controlling devices being in series arrangement, whereby their effect is cumulative.

18. An automatic musical instrument comprising an exhaust air-pump and means for varying the degree of air-tension produced by said air-pump comprising a chamber in communication with said air-pump and having an air-admission port, and means for controlling said port including a valve, a member movable in one direction to open said valve, and yieldable means through which said member may, upon movement in another direction, hold said valve to yieldingly obstruct the flow of air through said port.

19. An automatic musical instrument comprising an exhaust air-pump and means for varying the degree of air-tension produced by said air-pump comprising a chamber in communication with said air-pump and having an air-admission port, and means for controlling said port including a valve, a member movable in one direction to open said valve, said member being movable also in a second direction, yieldable means through which said member may, upon movement in said second direction, hold said valve to yieldingly obstruct the flow of air through said port, and a stop for limiting the movement of said member in second direction.

20. An automatic musical instrument comprising an exhaust air-pump and means for varying the degree of air-tension produced by said air-pump comprising a chamber in communication with said air-pump and having an air-admission port, and means for controlling said port including a valve, a member movable in one direction to open said valve, said member being movable also in a second direction, yieldable means through which said member may, upon movement in said second direction, hold said valve to yieldingly obstruct the flow of air through said port, and an adjustable stop for limiting the movement of said member in second direction.

21. An automatic musical instrument comprising an exhaust air-pump and means for varying the degree of air-tension produced by said air-pump comprising a chamber in communication with said air-pump and having an air-admission port, and means for controlling said port including a valve, a member movable in one direction to open said valve, yieldable means through which said member may, upon movement in an

other direction, hold said valve to yieldingly obstruct the flow of air through said port, 65 and a dash-pot member for said valve to prevent fluttering of the valve.

22. An automatic musical instrument comprising an exhaust air-pump and means for varying the degree of air-tension produced 70 by said air-pump comprising a chamber in communication with said air-pump and having an air-admission port, and means for controlling said port including a valve, a member movable in one direction to open 75 said valve, yieldable means through which said member may, upon movement in another direction, hold said valve to yieldingly obstruct the flow of air through said port, and a bellows dash-pot member for 80 said valve to prevent fluttering of the valve.

23. An automatic musical instrument comprising an exhaust air-pump and means for varying the degree of air-tension produced 85 by said air-pump comprising a chamber in communication with said air-pump and having an air-admission port, and means for controlling said port including a valve, a member movable in one direction to open 90 said valve, yieldable means through which said member may, upon movement in another direction, hold said valve to yieldingly obstruct the flow of air through said port, a dash-pot member for said valve to prevent fluttering of the valve, and means 95 for actuating said movable member.

24. An automatic musical instrument comprising an exhaust air-pump and means for varying the degree of air-tension produced 100 by said air-pump comprising a chamber in communication with said air-pump and having an air-admission port, and means for controlling said port including a valve, a member movable in one direction to open 105 said valve, yieldable means through which said member may, upon movement in another direction, hold said valve to yieldingly obstruct the flow of air through said port, a dash-pot member for said valve to prevent fluttering of the valve, and a pneumatic 110 for actuating said movable member.

25. An expression device for varying the degree of air-tension produced by an air-pump, comprising a chamber in communication with said air-pump and having an air-admission port, and means for controlling 115 said port including a valve, a member movable in one direction to open said valve, and yieldable means through which said member may, upon movement in another direction, 120 hold said valve to yieldingly obstruct the flow of air through said port.

In witness whereof, I have hereunto subscribed my name.

ALFRED SWENSEN.
